Primary Examiner — Cynthia Ramirez*Assistant Examiner* — Llorellys Martinez-Rivera(74) *Attorney, Agent, or Firm* — Egbert Law Office, PLLC(57) **CLAIM**

The ornamental design for a bracelet, as shown and described.

DESCRIPTION

FIG. 1 is a perspective view of a bracelet showing our new design.

FIG. 2 is a perspective view of the bracelet shown in condition of use.

FIG. 3 is a top view thereof;

FIG. 4 is a bottom view thereof;

FIG. 5 is a side view thereof;

FIG. 6 is an opposite view thereof.

FIG. 7 is a front thereof; and,

FIG. 8 is a rear view thereof.

The broken line text and cross surface ornamentation in FIGS. 1 and 3 of the drawings represent unclaimed portions of the bracelet and form no part of the claimed design. The dashed lines in FIGS. 1-4 represent stitching.

1 Claim, 2 Drawing Sheets(56)
